UNITED STATES PATENT OFFICE

FREDERICK W. ROBERTSHAW, OF PITTSBURGH, PENNSYLVANIA

THREADING TOOL

Application filed February 16, 1927. Serial No. 168,571.

The present invention relates broadly to the art of metal working, and more particularly to an improved tool by means of which threads may be quickly and accurately formed on any desired article, the tool preferably being of such construction that after a thread of initially predetermined length has been cut on such article, further cutting operation is made impossible. This operation is obtained without losing the setting of any of the tool parts.

The present invention is particularly adapted for use in the formation of relatively short threads on articles of comparatively large diameter, such as caps, plugs, closures, and the like, although the utility of the invention is not limited in this respect.

It is customary, in the art to which the present invention relates, to provide so-called releasable threading dies in which the dies are automatically collapsed or expanded after a predetermined threading operation, whereby the maximum length of thread is definitely controlled. Experience has shown, however, that while tools of this general character operate at a high speed to cut threads of the length required, the cutting dies are not always reset to exactly their original setting, with the result that successive articles have threads formed thereon differing in actual overall diameter by amounts varying from a fraction of a thousandth of an inch to several thousandths of an inch. While this is not particularly objectionable where a tapered thread is being cut, it is decidedly objectionable in articles requiring a substantially straight thread. Also, with tools having these general characteristics, the frequent adjustment of the parts, together with the automatic release and resetting for each thread-cutting operation, soon produces sufficient looseness to prevent the subsequent precision operation thereof.

The present invention has for one of its objects the provision of a thread-cutting tool adapted to be initially set to cut a thread of the required diameter, and thereafter retain such setting for as long a period as desired.

In this respect the present tool embodies the

desirable characteristics of a fixed threading die.

It is further desirable, however, to provide a tool in which adjustment is possible at will, and one of the objects of the present invention is to provide a tool in which the cutting dies may be easily adjusted to increase or decrease the diameter of the thread formed thereby.

Still another object of the invention is to combine the foregoing characteristics in a tool capable of automatically releasing itself after a thread of the desired length has been cut thereby, such a tool being particularly adaptable for use on a lathe or similar machine operating at a comparatively high speed.

In the accompanying drawings there is shown, for purposes of illustration only, a preferred embodiment of the present invention, it being understood that the drawings do not define the limitations of my invention, as changes in the construction and operation disclosed therein may be made without departing either from the spirit of the present invention or the scope of my broader claims.

In the drawings,

Figure 1 is an elevation of a tool embodying the present invention;

Figure 2 is a longitudinal sectional view on the line II-II of Figure 1 looking in the direction of the arrows;

Figure 3 is a perspective view of the die head;

Figure 4 is a perspective view of the knockoff ring;

Figure 5 is an elevation of the regulating and adjusting ring;

Figure 6 is a detail sectional view, on an enlarged scale, on the line VI-VI of Figure 5;

Figure 7 is a side elevation of the expanding screw for the regulating and adjusting ring;

Figure 8 is a side elevational view of the clutch pin; and

Figure 9 is a transverse sectional view on the line IX-IX of Figure 2.

In carrying out the present invention, there may be provided a supporting arbor 2 of any desired construction, having formed

at an intermediate portion thereon a collar 3 formed on its outer face with one or more grooves or recesses 4. Projecting beyond the collar 3 is a bearing portion 5 adapted to form 5 a support for certain of the parts of the improved threading tool.

Surrounding the bearing 5 is a knockoff ring 6, illustrated in perspective in Figure 4. This ring is formed with an enlarged base portion 10 carrying one or more driving lugs 8 adapted to cooperate with the grooves or recesses 4, as illustrated in dotted lines in Figure 2. The knockoff ring has an outer diameter such that it is adapted to accurately fit within a die head 9 and properly center the same, the die head and knockoff ring being held in assembled relation by means of one or more set screws or similar means 10.

The die head comprises a generally annular body having formed therein and extending completely through the walls thereof throughout a portion of its length only, a plurality of die-receiving grooves 11. Any number of such grooves may be formed in 25 the head in accordance with the number of dies which it is desired to utilize for the threading operation.

After the knockoff ring 6 has been placed in position around the bearing portion 5, 30 the clutch pin 12, shown in detail in Figure 8, is slipped into position through a suitable opening in the arbor, and is held in the desired position by a set screw 13 adapted to engage a depression 14 in the pin. With these 35 parts in position, the die head may be slipped over the knockoff ring and secured thereto by the screws 10. Thereafter a regulating and adjusting ring 15, having an internal diameter substantially conforming to the outer 40 diameter of the bearing portion 5, may be slipped over the bearing portion into the general position illustrated in Figure 2. This regulating and adjusting ring is divided into a number of sections corresponding to the 45 number of die-receiving grooves 11 in the head 9. In the embodiment illustrated in detail in Figure 5, these sections are shown as being separated by axially extending grooves 16. Each of the sections is provided 50 with threads 17 throughout the entire area thereof or throughout any predetermined portion thereof. Where the threads extend continuously, it is desirable to have certain portions thereof cut away to provide bearing zones 18. These bearing zones are adapted, 55 when the regulating and adjusting ring is expanded, to bear against the inside of the die head 9, as clearly indicated in Figure 1.

The threads on each section of the regulating and adjusting ring are formed so that at one end they are closer to the center of the ring than they are at the opposite end, the major portion of the length of the threads 60 on each section forming a cam effective upon 65 rotation to provide a surface at varying dis-

tances from the center of the ring for the purpose hereinafter more fully pointed out.

With the foregoing parts in position, a threading die 19 is slipped into position in each of the grooves 11 in the die head. These dies all have the same characteristics and each has a length materially greater than the length of the thread which it may be desired to form on a given article, such, for example, as the cap C indicated in chain lines in Figure 2. After the cutting dies have been approximately positioned in the grooves 11, each of the adjusting screws 20 is set up to engage the back of its corresponding die and hold the same against outward displacement. 70 The screws 20 are carried by a supporting ring 21 which surrounds the die head and is held in position thereon by a suitable set screw 22. By rotating the regulating and adjusting ring 15 in one direction or the other, the extent to which the cutting dies 19 may be inwardly adjusted is varied. The ring 15 will have threads thereon of exactly the same pitch as the threads 23 on the dies 19, whereby engagement between the 75 threaded portions of each will properly adjust the cutting dies. This axial adjustment of the cutting dies will so position them that they will properly cooperate with the article to be threaded and each form threads 80 in the proper position. After all the parts have been adjusted as desired, the expanding screw 24 carried by the ring 15 is threaded downwardly to cause the tapered head portion thereof to engage the tapered walls 25 of the ring and expand the same to lock it in position, this expansion being permitted by reason of the fact that the ring is split transversely as indicated at 26.

In operation, after the tool has been assembled, the arbor 2 is placed in a lathe or other machine, and the lathe operated to rotate the arbor, and by reason of the lugs 8 to also rotate the knockoff ring 6 and the die head 9. This in turn causes rotation of the cutting dies and of the ring 15. This rotation continues until the thread being cut effects axial movement of the rotating cutting head assembly along the bearing portion 5 of the arbor to such an extent as to effect dis-engagement between the lugs 8 and the recesses 4, the actual length of engagement between the lugs 8 and recesses 4 determining the length of the thread cut. After disengagement the arbor will turn without effecting any turning of the knockoff ring and its associated parts. This condition will continue until the operator effects axial movement of the arbor 2 in a direction the reverse of that in which the knockoff ring 6 moved to effect disengagement of the lugs 8 from the recesses 4, as indicated by the arrow B in Figure 2. This movement will bring the ends of the clutch pin 12, which overlaps the 105 110 115 120 125 130

ring 6, into engagement with the sides of the lugs 27 on the face of the knockoff ring opposite the lugs 8. Prior to this time the direction of rotation of the arbor 2 will have been changed, so that when the pin 12 engages the lugs 27, the cutter assembly will be rotated in a direction to unscrew it from the thread which it has formed on the article being threaded.

It will be apparent to those skilled in the art that instead of actually rotating the arbor in the manner herein specifically described, the arbor may be held stationary, as, for example, in the head of a turret lathe, and the work to be threaded may be rotated relatively thereto. The initial rotation of the work will effect a longitudinal movement of the cutting head assembly along the bearing portion 5 of the arbor until such time as the lugs 8 become disengaged from the recesses 4. After this disengagement has taken place, the cutting head assembly will rotate freely with the work without performing any cutting operation. This will continue until such time as the arbor 2 is moved in the direction of the arrow B of Figure 2, or until the work is moved in the reverse direction so as to cause the pin 12 to engage the lugs 27. Prior to such time, however, the direction of rotation of the work will have been changed, so that when the pin 12 and the lugs 27 come into engagement the cutting head assembly will be rotated in the reverse direction such that it will be unscrewed from the previously threaded work.

In either case the length of thread cut may be variably controlled by placing any desired number of shims in the bottoms of the recesses 4. The thicker the shims, the shorter the axial movement required to effect disengagement of the lugs 8 from the recesses, and therefore the shorter the thread.

With the construction shown, should the thread which is cut be of too great diameter, the screw 24 is loosened, the screws 20 backed off, the ring 15 rotated in a clockwise direction as viewed in Figure 1, and the parts again adjusted. On the other hand, if the thread is of too small diameter, the ring is rotated in the opposite direction.

Should any cutting die become broken at any time, its corresponding screw 20 may be backed off without releasing any of the other cutters, and a new cutter quickly placed in position.

The cutting dies are at all times rigidly held in a given position, insuring the formation of perfect threads, and by reason of the automatic action of the knockoff ring, these threads may be formed at high speeds without fear of breakage of the tool.

When cutting straight threads, the cutting dies may be sharpened without removal

from the die head by simply regrinding the outer ends thereof. This regrinding effects resharpening under such conditions, for the reason that the first thread on each cutter affects the entire cutting operation. With such straight or parallel threads, the face or flat part of each of the cutters never requires any regrinding. With tapered threads the cutters must necessarily be individually removed and touched up on the face, as in such case all of the teeth throughout the length of the projecting portion of the cutters in engagement with an article at any given time are effective on such article. In any case, in addition to the regrinding of the ends, they may be ground on the threaded faces to relieve the same to an extent necessary to facilitate starting of the thread-cutting operation.

Certain advantages of the present invention arise from the use of a rigid tool easily adjusted and capable of being operated at high speeds to effect a thread-cutting operation throughout a predetermined part of an article.

Other advantages arise from the provision of automatically stopping the cutting operation after a thread of the desired length has been cut without the necessity of collapsing or releasing the cutters, or in any manner destroying their original setting.

Other advantages of the invention arise from the provision of means for accurately adjusting the position of individual cutters both axially and radially.

Still other advantages arise from the provision of cutters so mounted that any cutter may be removed at will, the cutters being so supported in position that when used for the cutting of straight or parallel threads they may be sharpened without removal.

I claim:

1. In a thread-cutting tool, a die head, a plurality of individually adjustable thread-cutting dies in said head, a regulating and adjusting ring cooperating with all of said dies, an arbor on which said head is axially movable, and means for operatively connecting said head and arbor at the limit of movement of the head on the arbor in either direction.

2. In a thread-cutting tool, a die head carrying a plurality of adjustable cutting dies, means for rigidly maintaining said dies in adjusted position, a driving arbor for said head, and a knockoff ring having means providing a driving connection between said arbor and said head and effective for releasing said head from said arbor after a thread of initially predetermined length has been cut by said head, said knockoff ring and said arbor being provided with other inter-engaging parts adapted to be engaged to effect removal of said cutting dies from a threaded article.

3. In a thread cutting tool, an arbor having an offset portion, a knockoff member having an offset portion adapted to engage said first-mentioned portion to provide a driving engagement between the arbor and the knock-off, and said arbor and knockoff each having other offset portions adapted to provide a second driving engagement therebetween, the respective offsets being engageable at will by relative axial movement between the arbor and the knockoff.

4. In a thread cutting tool, an arbor having an offset portion, a knockoff member having an offset portion adapted to engage said first-mentioned portion to provide a driving engagement between the arbor and the knock-off, and said arbor and knockoff each having other offset portions adapted to provide a second driving engagement therebetween, the respective offsets being engageable at will by relative axial movement between the arbor and the knockoff, said knockoff comprising a ring-shaped member surrounding the arbor intermediate the offset portions thereon, and movable therebetween.

5. In a thread cutting tool, a driving arbor, a die head carrying a plurality of adjustable cutting dies and rotatably mounted on said arbor, means for rigidly maintaining said dies in adjusted position, and a knock-off ring surrounding said arbor and constituting a driving connection between said arbor and head and effective for releasing said head from said arbor after a thread of initially predetermined length has been cut by said head, said arbor having other means adapted to engage said ring after a thread of predetermined length has been cut and rotate said head in a direction opposite to its thread cutting direction when the arbor is rotated to back off the tool.

6. In a thread cutting tool, an arbor having axially spaced driving means thereon, a knock-off member movable axially of the arbor for engagement with either of said driving means at will, said knock-off member being driven entirely by said arbor, and a threading means operatively connected to said knock-off member and continuously rotated thereby when said member is rotated, one of said driving means extending transversely of the arbor and radially into overlapping relationship to the knock-off member to exert a backing off pull thereon.

55 7. In a thread cutting tool, an arbor having axially spaced driving means thereon, a ring-shaped knock-off member surrounding the arbor and axially movable along the arbor for engagement with either of said driving means at will, said knock-off member being driven entirely by said arbor, and a threading means operatively connected to said knock-off member and continuously rotated thereby when said member is rotated, one of said driving means extending transversely of the ar-

bor and radially into overlapping relationship to the knock-off member to exert a backing off pull thereon.

In testimony whereof I have hereunto set my hand.

FREDERICK W. ROBERTSHAW.
